UNITED STATES PATENT OFFICE.

VOJTECH PACHNER, OF CHICAGO, ILLINOIS.

DESIGN FOR A ROTARY GRATER-CASING.

49,619.

Specification for Design.

Patented Sept. 5, 1916.

Application filed December 11, 1915. Serial No. 66,385. Term of patent 3½ years.

To all whom it may concern:

Be it known that I, VOJTECH PACHNER, a subject of the Emperor of Austria-Hungary, residing at Chicago, in the county of Cook and State of Illinois, have invented a new, original, and ornamental Design for a Rotary Grater-Casing, of which the following is a specification, reference being had to the accompanying drawing, forming part thereof.

Figure 1 shows a front elevation of my

design for a rotary grater casing. Fig. 2 a side elevation. Fig. 3 a view taken on line 3—3 of Fig. 2 showing one arm of the support.

I claim:

The ornamental design for a rotary grater casing as shown.

In witness whereof, I have hereunto subscribed my name this 6th day of December, 1915.

VOJTECH PACHNER.
